(57) **ABSTRACT**

A crossbow may include a main beam; a compound bow assembly mounted to the main beam including a riser and a pair of bow limbs; and a trigger mechanism mounted to the main beam for use in holding a bowstring in a cocked position. The crossbow may include wheels at opposite ends of the bow that operatively receive the bowstring. The wheels may be separated by a wheel distance (WD) when the crossbow is in an un-cocked position. The crossbow may also have a power stroke distance (PD) and the ratio WD/PD may be less than 2.0. The crossbow may include a foot stirrup being integral with the riser, the foot stirrup beginning behind the pair of bow limbs and extending beyond the bow limbs.

NARROW CROSSBOW WITH LARGE POWER STROKE

This application claims priority from U.S. Ser. No. 60/868,157, entitled CROSSBOW, filed Dec. 1, 2006, which is incorporated herein by reference.

I. BACKGROUND OF THE INVENTION

A. Field of Invention

This invention relates to apparatuses and methods regarding crossbows and more specifically to apparatuses and methods regarding a narrow crossbow having a large power stroke.

B. Description of the Related Art

Crossbows have been used for many years as a weapon for hunting and fishing, and for target shooting. In general, a crossbow includes a main beam including a stock member and a barrel connected to the stock member. The barrel typically has an arrow receiving area for receiving the arrow that is to be shot. The crossbow also includes a bow assembly supported on the main beam that includes a bow and a bowstring connected to the bow for use in shooting arrows. A trigger mechanism, also supported on the main beam, holds the bowstring in a drawn or cocked condition and can thereafter be operated to release the bowstring out of the uncocked condition to shoot the arrow. One characteristic of a crossbow is termed a power stroke. The power stroke is the distance along the main beam that the bowstring moves between the uncocked condition and the cocked condition.

One of the trends in the industry today is to advertise very large power strokes, such as 16 inches, 17 inches or 18 inches. Such very large power strokes provide the potential for more speed and energy. But there are corresponding problems. One such problem is the added difficulty in manually cocking the crossbow. More specifically, the operator must have relatively long arms in order to properly reach the bowstring for cocking purposes. Another problem with relatively large power strokes is the increased angle of the bowstring when placing it into the cocked position. This also makes it more difficult to cock the crossbow.

Another problem with known crossbows is related to their width. More specifically, to obtain an adequate power stroke it is known to provide crossbows that are relatively wide. Such wide crossbows may be difficult for a hunter to operate while following prey, side to side, because the crossbow is less maneuverable and the hunter is more likely to bump into surrounding objects.

What is needed is a relatively narrow crossbow having a relatively large power stroke. In this way the disadvantages known in the art can be overcome in a way that is better, more efficient and that provides better overall results.

II. SUMMARY

According to one embodiment of this invention, a crossbow includes: a main beam; a compound bow assembly mounted to the main beam and having: (a) a bow; (b) a bowstring for use in propelling an arrow and operatively connected to the bow; and, (c) first and second wheels at opposite ends of the bow that operatively receive the bowstring, each of the first and second wheels pivoting about a pivot axis, the pivot axes being separated by a wheel distance (WD) when the crossbow is in an un-cocked position; and, a trigger mechanism mounted to the main beam for use in holding the bowstring in a cocked position. The crossbow may have a power stroke distance (PD) the ratio WD/PD may be less than 2.0.

2

According to another embodiment of this invention, the ratio WD/PD is less than 1.8.

According to another embodiment of this invention, the ratio WD/PD is less than 1.6.

According to yet another embodiment of this invention, a bow assembly includes: a riser having a first end with a first pocket and a second end with a second pocket; a first limb having a first end received in the first pocket, a hinge point, and a second end; a second limb having a first end received in the second pocket, a hinge point, and a second end; a bowstring for use in propelling an arrow and operatively connected to the first limb and to the second limb; and, wherein the first limb has a length, a height and a thickness, and the thickness of the first limb varies continuously along its length from its first end to its hinge point.

According to another embodiment of this invention, a crossbow includes: a main beam having a first end; a bow assembly having: (a) a bow with: (1) a riser having a first end with a first pocket, a second end with a second pocket, a connection portion for use in connecting the riser to the first end of the main beam, and an opening defining a foot stirrup for use in cocking the crossbow, wherein the opening is positioned at least partially directly between the first and second pockets; (2) a first limb having a first end received in the first pocket and a second end; (3) a second limb having a first end received in the second pocket and a second end; (b) a bowstring for use in propelling an arrow and operatively connected to the second ends of the first and second limbs; and, a trigger mechanism mounted to the main beam for use in holding the bowstring in a cocked position.

According to yet another embodiment of this invention, the foot stirrup is made with the riser as a single piece.

According to another embodiment of this invention, a compound bow assembly includes: a bow; a bowstring for use in propelling an arrow and operatively connected to the bow; first and second wheels at opposite ends of the bow that operatively receive the bowstring; wherein the first wheel has first and second sides and an opening that receives a first shaft defining a first pivot axis about which the first wheel rotates; and, a first bushing having an opening that receives the first shaft, the first bushing having a first end that is received within the opening in the first wheel and a second end that has a flange that contacts the first side of the first wheel.

One advantage of this invention according to one embodiment is that a relatively narrow crossbow having a relatively large power stroke is provided.

Another advantage of this invention is that a crossbow may be easy to manually cock.

Another advantage of this invention is that the crossbow is easy to maneuver.

Still another advantage of this invention is that compound bow vibrations may be reduced.

III. BRIEF DESCRIPTION OF THE DRAWINGS

The invention may take physical form in certain parts and arrangement of parts embodiments of which will be described in detail in this specification and illustrated in the accompanying drawings which form a part hereof and wherein:

FIG. 1 is a top perspective view of a crossbow according to certain embodiments of the invention.

FIG. 2 is a side view of a crossbow similar to that shown in FIG. 1. The paragraph

FIG. 3 is a top view of the crossbow of FIG. 2, showing the crossbow in the cocked condition.

FIG. 4 is a perspective end view of the crossbow shown in FIG. 3.

FIG. 5 is a perspective end view of a portion of the crossbow showing the compound bow.

FIG. 6 shows limb dimensions according to one embodiment of this invention.

FIG. 7 is a close-up top perspective view of a riser according to one embodiment of this invention.

FIG. 8 is a perspective view of a crossbow showing how a foot stirrup may engage a ground surface.

FIG. 9 is a close-up top perspective view showing how the bow limbs may be received within riser pockets according to one embodiment of this invention.

FIG. 10 is a close-up top perspective view showing how the riser may be connected to the main beam according to one embodiment of this invention.

FIG. 11 is a close-up end view of the riser shown in FIG. 10.

FIG. 12 shows various riser views and dimensions according to one embodiment of this invention.

FIG. 13 is a perspective side view of two wheels according to one embodiment of this invention.

FIG. 14 is a top view of the wheels shown in FIG. 13.

FIG. 15 is a perspective top view wheels shown in FIG. 13.

FIG. 16 shows various wheel views and dimensions according to one embodiment of this invention.

FIG. 17 illustrates how bushings may be positioned within one of the pulley wheels according to one embodiment of this invention.

FIG. 18 is a close-up perspective view showing how a wheel may be attached to the crossbow limbs and to the bowstring.

FIG. 19 is a top view of the wheels shown in FIG. 18.

FIG. 20 is a top view of another wheel attached to crossbow limbs and to the bowstring.

IV. DEFINITIONS

The following definitions are controlling for the disclosed invention:

“Arrow” means a projectile that is shot with (or launched by) a bow assembly.

“Bow” means a bent, curved, or arched object.

“Bow Assembly” means a weapon comprising a bow and a bowstring that shoots or propels arrows powered by the elasticity of the bow and the drawn bowstring.

“Bowstring” means a string or cable attached to a bow.

“Compound Bow” means a crossbow that has wheels, pulleys or cams at each end of the bow through which the bowstring passes.

“Crossbow” means a weapon comprising a bow assembly and a trigger mechanism both mounted to a main beam.

“Draw Weight” means the amount of force required to draw or pull the bowstring on a crossbow into a cocked condition.

“Main Beam” means the longitudinal structural member of a weapon used to support the trigger mechanism and often other components as well. For crossbows, the main beam also supports the bow assembly. The main beam often comprises a stock member, held by the person using the weapon, and a barrel, used to guide the projectile being shot or fired by the weapon.

“Power Stroke” means the linear distance that the bowstring is moved between the uncocked condition and the cocked condition.

“Trigger Mechanism” means the portion of a weapon that shoots, fires or releases the projectile of a weapon. As applied to crossbows, trigger mechanism means any device that holds the bowstring of a crossbow in the drawn or cocked condition

and which can thereafter be operated to release the bowstring out of the drawn condition to shoot an arrow.

“Weapon” means any device that can be used in fighting or hunting that shoots or fires a projectile including bow assemblies and crossbows.

V. DETAILED DESCRIPTION OF THE INVENTION

Referring now to the FIGURES wherein the showings are for purposes of illustrating multiple embodiments of the invention only and not for purposes of limiting the same, FIGS. 1-4 show a crossbow 10 according to one embodiment of this invention. While the crossbow shown uses a compound bow, it should be understood that this invention will work well with any type of crossbow chosen with sound engineering judgment. The crossbow 10 has a main beam 12 including a stock member 14 and a barrel member 16. The main beam 12 may be made by assembling the stock member 14 and the barrel member 16 together as separate components or, in another embodiment, the main beam 12 may be made as one piece. A handgrip 18 may be mounted to the main beam 12 in any conventional manner. A trigger mechanism 20 suitable for shooting an arrow is mounted to the main beam 12 in any suitable manner. It should be noted that this invention will work well with any trigger mechanism chosen with sound engineering judgment. The crossbow 10 also includes a bow assembly 30 adapted to propel an arrow and having a bow 32 and a bowstring 34. The bow 32 includes a pair of limbs 36, 36 that receive the bowstring 34 in any conventional manner. For the embodiment shown, a pair of wheels or pulleys 38, 38 mounted to the limbs 36, 36 receive the bowstring 34 in a known manner. The bow may also include a riser or block 40 having a pair of limb pockets 42, 42 that receive the limbs 36, 36, as shown. Many other crossbow components may be optionally used with a crossbow using this invention. The crossbow 10 shown, for example, includes a scope 50 attached to a scope mount 52 that is supported on the main beam 12, and one or more swivel studs 54 (see FIG. 2). Other optional components shown include a cocking unit 56 and an arrow retention spring 58. As the operation of these components is well known to those of skill in the art, no further details will be provided.

FIG. 1 shows the crossbow 10 in an uncocked condition while FIGS. 2-4 show the crossbow 10 in a cocked condition. The power stroke is thus shown, in FIG. 1, with reference PD. For this invention the power stroke PD is at least 10 inches. In a more specific embodiment the power stroke PD is at least 12 inches. In yet a more specific embodiment the power stroke PD is about 13 inches. With reference to FIGS. 2 and 4, each wheel 38, 38 pivots about a pivot axis A-A. When the crossbow 10 is in the uncocked condition, the distance between the two pivot axes is shown with reference WD, see FIG. 1. To illustrate the relative narrow design of the crossbow according to this invention, in one embodiment the ratio WD/PD is less than 2.0. In a more specific embodiment the ratio WD/PD is less than 1.8. In getting more specific embodiments the ratio WD/PD is less than 1.6.

With reference now to FIGS. 1-6, a limb design according to one embodiment of this invention will now be described. Each limb 36 has a first end 60 that is received within the corresponding pocket 42 and a second end 62 that is operatively connected to the bowstring 34. Each limb 36 also has, as seen the best in FIG. 6, a length L1, a height H1 (measured from bottom to top when the crossbow is held in the normal operating position), and a thickness T1. Each limb 36 also has a hinge point HP which is the point along the length L1 at

which the thickness $T1$ is at a minimum. It should be noted that the thickness $T1$ of the limb **36** according to one embodiment varies continuously along its length $L1$ from the first end **60** to the hinge point **HP**. This is believed to be a first in the industry as known limbs maintain a constant thickness for at least a portion (2 to 4 inches, for a non-limiting example) of the pocket engaging end. Applicants have discovered, however, that the use of a varied thickness at the first end limb provides unexpected advantages. Specifically, the varied thickness provides limbs that can withstand greater bending forces prior to failing under load and reduced vibrations. The position of the hinge point **HP** to respect to the first end **60** of the limb **36** can be any chosen with sound engineering judgment. In one embodiment, shown, the hinge point **HP** is at least 6 inches from the first end **60** of the limb **36**. It should also be noted that the pockets **42** were not modified. Thus, it is clear that the varied thickness limbs provide the advantage. As a result, the limb length $L1$ can be shorter than previously thought possible. This also may contribute to the reduced ratio WD/PD described above. In one embodiment, the limb length $L1$ may be less than 15 inches. Any more specific embodiment, the limb length $L1$ may be less than 13 inches. In yet a more specific embodiment, shown in FIG. 6, the limb length $L1$ may be about 12 inches.

With reference now to FIGS. 2 and 5, in another embodiment each pocket **42** has first and second portions **42a**, **42b**. Each of these portions **42a**, **42b** receives a separate limb **36**. In this way, the crossbow **10** may use dual limbs on each end of the riser **40**. It should be noted that these inventive limb designs are not only applicable to a crossbow but would also apply to a compound bow or other bows when applied with sound engineering judgment.

With reference now to FIGS. 1-4 and 7-12, a riser design according to one embodiment of this invention will now be described. The riser **40** may have a first end **64** with one pocket **42** and a second end **66** with another pocket **42**. The riser **40** may also include a connection portion **68** for use in connecting the riser **40** to the first end **11** of the main beam **12**. The connection portion **68** may be connected to the main beam **12** in any manner chosen with sound engineering judgment such as using bolts. The riser **40** may include one or more cutouts **70** in order to minimize the riser materials required while still providing sufficient strength. An opening **72** may be formed in the riser **40** and may define a foot stirrup **74** which is used, as is well known, in cocking the crossbow **10**. In one embodiment, the opening **72** is positioned at least partially directly between the pockets **42**, **42**. This arrangement provides an opening **72** sufficient to receive most boot sizes yet simultaneously provides a reduced overall length for the crossbow **10** making it easier to manually cock the bowstring **34**. In another embodiment, the pockets **42**, **42** extend at least partially longitudinally beyond the first end of **11** off the main beam **12**. This arrangement also provides for an overall reduced length for the crossbow **10**. In yet another embodiment, the foot stirrup **74** is made with the riser **40** as a single piece. This permits, for one non-limiting example, the riser **40** and the foot stirrup **74** to be machined from a single piece of material. In one embodiment, the foot stirrup **74** comprises a generally U-shaped member extending from the riser body. The U-shaped member has a pair of leg portions **110**, **110** and a mid-portion **112**. The mid-portion **112** has an outer surface **114** that is substantially planar and is used in contacting a ground surface (as shown in FIG. 8) when cocking the crossbow **10**. The mid-portion **112** in one embodiment is on the same plane as the leg portions **110**, **110**. In another embodiment, shown, the mid-portion **112** has an offset **116**.

This offset **116** permits the crossbow **10** to be easily balanced on a ground surface when a user is cocking the crossbow **10**. As shown in FIGS. 11-12, the offset **116** may extend downwardly. In one embodiment the leg portions **110**, **110** extend substantially perpendicular from an inner surface of the mid-portion **112**. In another embodiment, shown, each leg portion **110** has an offset **118** that may extend outwardly. This offset **118** permits the opening **72** to be larger to thereby receive a user's foot that is larger and also provides for a longer mid-portion **112** that assists in balancing the crossbow **10** to a ground surface. It should be noted that this inventive riser design is not only applicable to a crossbow having a compound bow but also to a crossbow having other bows when applied with sound engineering judgment.

With reference now to FIGS. 1-4 and 13-20, a wheel design according to one embodiment of this invention will now be described. The wheel **38** may have first and second sides **82**, **84** and an opening **b** (referenced in FIG. 16). The opening **86** is used to receive a shaft **88** that is operatively connected to the limbs **36** of the crossbow **10**. The wheel **38** may then rotate about the shaft **88** any manner well known in the choose one. Rather than having the wheel opening **86** rotate directly around the shaft **88** as is commonly known, at least one bushing **90** may be used. The bushing **90**, as seen in best in FIG. 17, may have an opening **92** that rotatably receives the shaft **88**. The bushing **90** may also have a first end **94** that is received within the opening **86** in the wheel **38** and a second end **96** that has a flange **100**. The flange **100** has an outer diameter that is greater than the outer diameter of the first end **94**. As a result, the flange **100** contacts the first side **82** of the wheel **38**. It is to be understood, however, that the outer shape of the bushing **90** need not be circular in cross-section, as shown, but could have other shapes. In another embodiment, a second bushing **90** may be inserted into the opposite end of the wheel opening **86**. In this case, the flange **100** contacts the second side **84** of the wheel **38**. In still another embodiment, there is a space **102** between the first end **94** of one bushing **90** and the first end **94** of the other bushing **90** when they are properly installed onto the wheel **38**. For the embodiments shown, each wheel **38** comprises a pair of pulleys and comprises a cam. It should be understood, however, that the bushings of this invention will work with wheels having any number of pulleys and wheels that may or may not comprise a cam. It should be noted that this inventive wheel design is not only applicable to a crossbow but would also apply to a compound bow when applied with sound engineering judgment.

Multiple embodiments have been described, hereinabove. It will be apparent to those skilled in the art that the above methods and apparatuses may incorporate changes and modifications without departing from the general scope of this invention. It is intended to include all such modifications and alterations in so far as they come within the scope of the appended claims or the equivalents thereof.

Having thus described the invention, it is now claimed:

1. A crossbow comprising:
a bow assembly including a riser and a pair of bow limbs;
a main beam having opposed longitudinal ends, including
a first end to which is mounted said bow assembly; and,
a foot stirrup mounted to said first end of said main beam
and being integral with said riser; said foot stirrup beginning
behind said pair of bow limbs and extending
beyond said bow limbs, such that a user's foot is insertable
into said foot stirrup to support the crossbow for
cocking.
